UNITED STATES PATENT OFFICE.

FRANK C. DELI, OF CHICAGO, ILLINOIS, ASSIGNOR TO AUTOPOINT COMPANY, OF CHICAGO, ILLINOIS, A CORPORATION OF ILLINOIS.

MECHANICAL PENCIL.

Application filed June 30, 1924. Serial No. 723,312.

This application is a continuation, so far as there is common subject matter, of co-pending application Serial No. 444,956, filed Feb. 14, 1921.

The mechanical construction of the pencil herein claimed was also fully disclosed in my copending application Serial No. 504,839, filed Oct. 2, 1921. The principle of operation of the said pencil was first disclosed in 10 my copending application Serial No. 406,980, filed August 30, 1920.

This invention relates to certain new and useful improvements in lead pencils of the magazine or mechanical type, commonly 15 called "Eversharp" pencils, and it consists in certain peculiarities of the construction, novel arrangement, combination and operation of the various parts thereof as will be hereinafter more fully set forth and specifically 20 claimed.

The principal object of my present invention is the production of a pencil of the above named type having the qualities of all adaptability that is required in pencils of 25 said class, at a minimum cost of manufacture and assemblage, without sacrificing any of its advantages or merits.

A further object is to provide such a pencil which shall be attractive in appearance, 30 strong, durable and highly efficient in operation, with its parts so made, arranged and operating, that a number of leads can be carried thereby, with one lead in operative position to be advanced through one end of the body of the pencil for use, or retracted when not in use, to prevent the point thereof being broken or impaired.

A further object is to provide means for actuating a plunger for the operative lead of 40 the pencil by the rotation of a shell or tip to cause said lead to be advanced or fed forwardly.

Still another object is to utilize a part of the plunger operating mechanism as a guiding support or holder for the operative lead.

Other objects of the invention will be obvious from the following description and explanation.

In the accompanying drawings which 50 serve to illustrate an embodiment of the invention;

Fig. 1 is a central longitudinal sectional view of one form of the invention, showing the parts in about the positions they will occupy when the operative lead of the pencil

is advanced through the front end of the latter sufficiently for writing purposes;

Figs. 2, 3 and 4 are cross sectional views taken on lines 2-2, 3-3, and 4-4 respectively of Fig. 1, looking in the direction indicated by the arrows; 60

Figs. 5 and 6 are cross sectional views taken on a line as at about 2-2 of Fig. 1, showing modified constructions of the parts comprising the barrel of the pencil; 65

Fig. 7 is a view similar to Fig. 1, but illustrating a modification in the construction of the barrel of the pencil;

Figs. 8, 9 and 10 are plan sectional views taken on the lines 8-8, 9-9, and 10-10 respectively of Fig. 7, and, 70

Fig. 11 is a detached view in elevation of the plunger operating mechanism and guide support for the operative lead, showing the plunger and said lead in their operative positions. 75

Similar numerals of reference refer to corresponding parts throughout the different views of the drawings.

Referring now more particularly to Figs. 1 to 6 inclusive of the drawings, the reference numeral 15 designates as a whole the barrel or body of the pencil which by preference is cylindrical in shape as shown. This barrel is provided at its upper or rear end with a reduced portion 16 on which is closely fitted a ferrule 17 which extends beyond the upper end of the barrel 15 and has fitted therein an eraser 18 of rubber or other suitable material. The barrel 15 is provided throughout its length with a bore which is transversely divided into compartments or portions of different sizes and shapes for the purposes to be presently explained. The lower or front end of the barrel 15 is provided with a reduced portion 19 for the reception and operation of the upper portion of a downwardly tapered operating shell or tip 20 which is by preference made of metal and has in its tapered end slits 21 to allow its tapered extremity to resiliently grip the operative lead 22 of the device. The bore or cavity in the upper portion of the barrel 15 is by preference circular in cross section, as shown in Fig. 2, and at the lower end of said circular part of the bore a disk or plate 23 is secured, which will form a floor or bottom for the circular compartment 24, thus adapting it for use or as 100 a magazine for the reception of a plurality

105

110

of leads 25, which can be inserted into the compartment or magazine 24 by removing the eraser 18 from the ferrule 17, or by removing the ferrule 17 with the eraser 18 5 therein from the upper portion of the barrel. The lower portion of the bore in the barrel 15 is circular in cross section, as shown at 26 in Fig. 4. The portion 26 of the bore extends from the lower end of the barrel 15 10 upwardly therein to a suitable distance, approximately about one-third of the length of the barrel. The intermediate portion 27 of the bore of the barrel is angular in cross section, and by preference rectangular, as 15 shown in Fig. 3 of the drawings, thereby forming a guideway. This angular portion of the bore extends from the upper end of the portion 26 of the bore to the lower end of the portion 24, or to the lower surface of 20 the disk or plate 23, which may rest on the upper ends of the walls of the angular portion 27. Located in the cavity of the shell 20 at the lower end of the cylindrical portion of said shell, which portion fits around 25 the reduced portion 19 of the barrel so as to present its outer surface flush with the outer surface of the barrel thus lending attractiveness to the structure, is a centrally apertured plate or disk 28, which is fixed to the 30 shell 20 and adapted to rotate therewith.

It will be noted that the tip frictionally engages the reduced portion 19 and is rotatable thereon and removable therefrom by a straight longitudinal pull.

35 Located in the portion 26 of the bore of the barrel and extended from the upper end of said portion through its lower end as well as through the aperture of the plate 28, and into the tapered cavity of the tip 20, where 40 it is secured thereto, is a tube 29 which is provided with a spiral groove or track 30 formed with a die, in the operation of which it will be understood that the walls of the groove 30 will be pressed inwardly of the tube thus forming a spiral guideway 31 on the inner surface of said tube for the reception and operation of the operative lead 22, as well as for the feeding plunger 32, which 45 has at its upper end an enlarged head 33 located in the angular portion or guideway 27 of the bore of the barrel which angular portion will cooperate with the head 33 so as to permit of longitudinal movement of said parts. The lower portion of the plunger 32 is provided with one or more laterally disposed offset portions 34 to engage the spiral channel 31 of the tube 29, as will be readily understood by reference to Figs. 1 and 7 of the drawings. The tube 29 is fixed to the 50 plate 28 so that it will turn with the shell 20 when the latter is rotated on the lower portion of the barrel. As the lower end of the plunger 32 rests on the upper end of the operative lead 22, it is manifest that by turning 55 the shell 20 in the proper direction, the

plunger 32 will be advanced by reason of its engagement with the spiral channel 30 of the tube 26, thus causing the operative lead to be fed forwardly. When it is desired to insert a lead into the shell 20 and lower end 70 of the tube 29, it is obvious that the plunger can be retracted by rotating the shell 20 in the proper direction, when a lead can be inserted into the free end of the shell 20 and lower end of the tube 29 until the upper end 75 of the said lead contacts with the lower end of the plunger. Obviously also, the tip, attached parts and plunger may be removed from the lower end of the body as a unit 80 in any position of adjustment of the parts and that when so removed the plunger may be retracted and removed from the open upper end of the tube and a renewal lead inserted in said open upper end.

In the construction now under consideration, that is to say, in the views illustrated in Figs. 1 to 6 inclusive of the drawings, it will be seen and understood that the barrel 15 is made of two pieces 35 and 36, and that these pieces are converse to one another and may be made of any suitable composition molded to the form desired. That is, the meeting edges of the pieces 35 and 36 constituting the barrel 15 are provided with interlocking recesses 37 and correspondingly 85 shaped projections 38 to fit in said recesses. These recesses and projections are disposed longitudinally on the meeting edges of the members 35 and 36 of the barrel and it will be readily understood that said members 90 can be cast in the same molds and be readily placed in position with respect to one another so as to form the barrel of the pencil.

In assembling the pieces 35 and 36 their meeting edges may be supplied with a suitable adhesive so that when they are placed in position as shown in the different views of the drawings, they will be securely connected together and that the interlocking arrangement or construction of their meeting edges 105 will prevent their displacement.

While I have illustrated in Figs. 2 to 4 inclusive, one of the edges of the member 35 as being provided with a single projection 38 and its other edge with a single recess 37 115 and have shown one of the edges of the member 36 provided with a single recess 37 and its other edge with a single projection 38, which projection and recesses cooperate with one another, yet, in some instances I 120 may vary the form employed for interlocking the meeting edges of the said pieces, for instance, as shown in Fig. 5, one of the edges of the member 35 may be provided with two projections 38 to fit in a corresponding number of recesses 37 on the adjacent edge of the member 36 and may provide the other edge of the member 35 with a pair of recesses 37 to receive a pair of projections 38 on the 125 adjacent edge of the member 36, or as shown 130

in Fig. 6, the meeting edges of the members 35 and 36 may be provided with angular offset recesses and correspondingly shaped projections to cooperate therewith.

- 5 In Figs. 7 to 10 inclusive I have illustrated a modification in the construction of the pencil which consists in making the barrel 39 of said modified form of a single piece of wood and externally of any desired shape 10 in cross section, but preferably hexagonal, as shown. In this modification the barrel 39 is formed and equipped with a ferrule 17 and an eraser 18, as in the first described construction, and likewise has a bore with 15 different sized and shaped compartments or portions 24, 26 and 27. The lower end of the barrel 39 is reduced and has fitted thereon a metal ferrule 40, on which the cylindrical portion of the shell 20 is fitted for rotation and removal, as will be understood by reference to Fig. 7 of the drawings. In this modified construction the compartment or portion 27 of the bore of the barrel is circular in cross section and has fitted therein 25 an angular tube 41, providing a guideway which extends from the floor or bottom 23 of the magazine or compartment 24 downwardly to the upper end of the portion 26 of the bore, which portion is equipped with 30 a metal tube 42 which extends to the lower end of the barrel 39 and within the tube 42 with a spirally grooved tube 29, which extends through an apertured disk or plate 28 fixed to the shell 20 in the upper portion of 35 the tapered part thereof and downwardly in said tapered portion. As in the other construction the disk or plate 28 is fixed to the tube 29, so as to turn with the shell 20. The plunger employed in the modified construction is similar to that illustrated in the first above described construction and operates in a similar manner.

40 From the foregoing it will be understood that by my improvements, a pencil of an 45 extremely simple construction and attractive

appearance will be provided, and that the cost of manufacturing the same will be reduced to a minimum.

I claim:—

1. In a pencil, the combination of a body 50 having an axial recess extending inwardly from both ends of the pencil, means providing a guideway in one portion of said recess, said body having a reduced lower end portion, a tip having a tapered portion and a generally cylindrical portion, said cylindrical portion overlying and frictionally engaging the reduced portion of the body, a tube open at both ends and projecting axially within the tip and secured thereto and provided with threads, and a plunger having a non-circular portion at its upper end adapted to cooperate with said guideway and at its lower end having a portion adapted to cooperate with said threaded tube, the tip, tube and plunger being removable from the lower end of the pencil in any position of adjustment of the parts.

2. In a pencil, the combination of a body 70 having an axial recess open at both ends of the body, a portion of the recess being non-circular in cross section, a tip having a cylindrical portion adapted to overlie and frictionally engage with the lower end of the body, a threaded lead receiving and guiding tube open at both ends and seated within and secured to the tip, and a plunger having a non-circular portion adapted to cooperate with the non-circular portion of the recess in the body and at its lower end having a lateral projection adapted to cooperate with the threads in the lead tube, the upper end of the recess in the body providing a space for reserve leads, the tip, tube and plunger being removable from the lower end of the 85 pencil by a direct endwise movement in any position of adjustment of the parts.

Signed at Chicago, Ill., this 31st day of May, 1924.

FRANK C. DELI.
